Primary Examiner — Ian Simmons*Assistant Examiner* — Carissa C Fitts*(74) Attorney, Agent, or Firm* — Barnes & Thornburg LLP**(57) CLAIM**

The ornamental design for an eccentric crown, as shown and described.

DESCRIPTION

FIG. 1 is a perspective view of an eccentric crown; FIG. 2 is a left side view thereof, the right side view being a mirror image thereof;

FIG. 3 is a top view thereof;

FIG. 4 is a bottom view thereof;

FIG. 5 is a front view thereof, the rear view being a mirror image thereof; and,

FIG. 6 is a perspective view of a crown.

The broken line showing represents portions of the article not claimed and forms no part of the claimed design.
